UNITED STATES PATENT OFFICE.

WILLIAM A. BERNARD, OF NEW HAVEN, CONNECTICUT, ASSIGNOR TO THE WILLIAM SCHOLLHORN COMPANY, OF NEW HAVEN, CONNECTICUT, A CORPORATION OF CONNECTICUT.

PUNCH.

SPECIFICATION forming part of Letters Patent No. 764,336, dated July 5, 1904.

Application filed April 17, 1903. Serial No. 153,089. (No model.)

To all whom it may concern:

Be it known that I, WILLIAM A. BERNARD, of the city and county of New Haven, State of Connecticut, have invented new and useful 5 Improvements in Punches, of which the following is a full, clear, and exact description when taken in connection with the accompanying drawings, which form a part thereof, and in which—

10 Figures 1 and 2 represent views, partly in side elevation and partly in longitudinal vertical section, through a punch embodying my invention, the punch being shown in its opened and closed positions, respectively; Fig. 3, an 15 enlarged detail view, in side elevation, of the gage; Fig. 4, a longitudinal vertical section through the same; Fig. 5, an end view of the same, and Fig. 6 a bottom view of the same.

10 In all figures similar letters of reference 20 represent like parts.

This invention relates to punches, and has for its object the production of a novel form of gage which has certain improvements in that it is adjustable, collapsible within itself, 25 and readily removed; and to this end it consists of the various improvements and combinations set forth and claimed hereinafter.

Referring to the drawings for a more particular description, the parts designated by 30 the letters A and B represent hollow lever-handles pivoted together at C and having their forward ends *a* and *b* pivoted at *a'* and *b'*, respectively, to the jaws D and E. The heels of the jaws extend into the hollow interior of the lever-handles A and B and have a 35 sliding connection therewith by means of slots *d* and *e* and pins *d'* and *e'* or in other suitable manner. By this means the jaws are given a movement parallel to each other upon the 40 opening and closing of the lever-handles A and B. The jaw E is provided at its forward end with a depending punch F, adapted to coact with a die G, correspondingly located in the jaw D. Between the jaws is located a gage 45 formed of two plates H and I, riveted or otherwise secured together at the rear. The plate H is substantially flat and is provided with a longitudinal slot *h* and at its forward end has

two laterally-upturned side plates *h'*. The central portion of its forward end is cut away 50 and upturned to form an engaging flange J, having an outwardly-projecting lip *j*. The plate I is bent to normally stand away from the plate H and is provided at its forward end with a downwardly-projecting depending flange *i*, which is provided with a rearwardly-engaging lip *i'*, adapted to interlock with the lip *j* of the flange J. The plates *h'* have their forward edges in the same plane as the front surface of the depending flange *i*, so that the forward end of the gage presents a substantially even vertical surface against which papers or other articles may be held while the punch is being operated. Upon the closing of the punch the plate I may be forced 65 toward the plate H, as shown more particularly in Fig. 2, so that only a small space is required between the jaws for the gage when the jaws are closed. On the other hand, when the jaws are open the plate I owing to its 70 resiliency will spring away from the plate H except as limited by the engagement between the lips *i'* and *j* to present a larger surface to the papers or other articles to be inserted in the punch. A set-screw K is adapted to pass through the jaw D and engage a nut or washer L to bind the gage in its desired position. The gage may be moved longitudinally on the jaw by slightly unscrewing the set-screw, which projects through the 75 slot *h*.

Having now described my invention, what I claim, and desire to secure by Letters Patent, is—

1. In a punch, or similar article, a collapsible gage, having two ends presenting gage-faces adapted to fold one within the other, whereby the face of the gage may be reduced, substantially as described. 85

2. In a punch, or similar article, an adjustable collapsible gage having two ends adapted to fold one within the other; and means for adjusting said gage longitudinally within said punch, substantially as described. 90

3. As an article of manufacture, a gage for 95 punches or similar articles, having two plates

forming gage-faces and normally tending to spread apart; an engagement between said plates for limiting the spreading of said plates, said plates being adapted to fold one within 5 the other to reduce the gage-face, substantially as described.

4. The combination with a punch or similar article; of a gage, having two plates normally tending to spread apart; means for limiting the 10 spreading of said plates, said plates being adapted to fold within each other and one plate being adapted to be adjustably secured to said punch, substantially as described.

5. As an article of manufacture, a gage for 15 punches or similar articles, consisting of two

plates secured together at one end and having their free ends form the gage-face, said plates normally tending to spread apart at the free ends, and having interlocking parts to limit said spreading movement, said plates 20 being adapted to fold one within the other to reduce said gage-face, substantially as described.

In witness whereof I have hereunto set my hand on the 14th day of April, 1903.

WILLIAM A. BERNARD.
